AUTOMATIC TRAIN PIPE COUPLING

Joseph Robinson, New York, N. Y., assignor of
one-half to Roy M. Wolvin, Montreal, Quebec,
Canada

Application December 16, 1930, Serial No. 502,761
Renewed July 12, 1933

6 Claims. (Cl. 285—58)

This invention relates to automatic train pipe couplings for railway cars. Among the objects is to provide an improved support for the coupling head of such devices, in which the head is pivoted on the forward end of the support to accommodate the automatic coupling to car coupler slip-bys without damage.

The novel means by which this object is accomplished is herein later described and is illustrated in the accompanying drawings in which

Figure 1 is a side elevation of my improvement;

Figure 2 is a sectional plan view thereof;

Figure 3 is a rear elevation of the funnel member of the coupling head;

Figure 4 is a sectional front elevation on the line 4—4 of Figure 2;

Figure 5 is a sectional plan view of a modification of my improvement; and

Figure 6 is a plan view of a modification of the plunger shown in the preferred form of my invention.

My improved coupling is supported from the car coupler in the usual manner as by a lug A welded to or formed integral with the coupler. My improvement may of course be otherwise attached to the car if desired. A bracket B is bolted or riveted to the lug and is so arranged

as to support the pin and funnel coupling head C on approximately the transverse center line of the coupler and with its coupling face a suitable distance in advance of the pulling face of the coupler. At its lower end the bracket is provided with a vertically extending lug or anchor device 6 preferably round in cross-section and having on its front face an indentation or recess forming a seat 7 (Figure 4) which pivotally receives the elongated perforated head 9 of a

tie rod D, the contacting faces of the tie rod and the seat being flared in opposite directions. The arrangement is similar to the construction shown in my Patent No. 1,908,866—the tie rod being provided with an adjustable abutment or

supporting nut 8 which positions the rear end of the spring F and by which the spring is placed under the desired initial compression in assembling the parts. Above and below the seat 7 the bracket is provided with crosswise extending

bars or projections 10 which constitute shoulders or supporting lugs. Between these, and spanning the lower portion of the bracket B, and the tie rod 9, I slidably mount a body or yoke E. The yoke is provided with spaced sides

55 or straps 11 which carry at their rear ends an

integral or otherwise arranged flange or projection 12, the straps 11 being widened at their point of connection with the flange to form positioning webs or fillers 14. These webs fit rather closely between the crossbars 10 and serve to prevent undue rotation of the yoke and the coupling head about their longitudinal axis when in the normal uncoupled position. To permit of substantial raising or lowering of the head C from the normal position (Figure 1) without too early losing the positioning effect of the widened portions 14 of the yoke E, I preferably extend such portions forwardly parallel with the yoke a short distance as at 15. Extending rearwardly from the rear side of the flange 12 I provide a barrel or sleeve 16 which receives the forward portion of the buffer spring F and guides and maintains the spring in position with respect to the yoke E when the coupling head C pivots to the position shown by the dot and dash lines in Figure 2. Between the rear side of the flange 12 and the front end of the spring F, and enclosing a portion of the spring, I provide a housing or plunger base 17. Projecting forwardly from one side of this housing I provide an arm or plunger 18 of any suitable cross section, preferably round or that of an I-beam. The arm passes through a recess or opening 19 in one side of the flange 12, Figure 4, and extends forwardly along one side of the yoke and through a properly fitted bearing formed in the tapered lug 19. The lug is integral with or otherwise connected to the yoke and projects away from one side thereof. A wide bearing surface for the plunger 18 is provided on the inner or bottom side of the lug, as at 20. As the coupling head C pivots to the position shown in dot and dash lines in Figure 2, the arm 18 slides along the bearing 20, for which reason the bearing is given considerable width. The base 17 is provided with an annular seat 21 for the spring F which seat slides freely over the guide or barrel 16 of the yoke. To strengthen the connection between the plunger 18 and the annular seat 21, I extend the housing wall to which is connected the arm 18 a considerably greater distance rearwardly than I do the opposite side of the housing, and for the same purpose I also provide a strengthened rib 22 which spans the connection between the arm 18 and seat 21.

At its forward end the yoke E is provided with a perforated head 23 which lies between rearwardly extending ears or lugs 24 formed on the rear side of the coupling head C. A suitable pivot pin 25 joins these parts as shown and is

suitably locked in place as by a cotter pin 26. Extending away from one side of the yoke I provide a rugged lug 27 the front face of which lies in the plane of the axis of the pivot pin 25. 5 A complementary bearing or lug 28 is provided on the rear side of the head C to abut the front face of this lug and thus properly position the head with respect to the yoke. With this arrangement it will be obvious that the head can- 10 not pivot to the right, viewed from the front, and that the head is held powerfully against the lug 27 by the constant forward thrust of the spring F, there being sufficient space between the housing plunger base 17 and the rear face of 15 the flange 12 of the yoke to always assure this. On its rear side or apex the funnel 29 of the coupling head C is provided with horizontally and vertically extending ribs 30 and 31 (Figures 1 and 3) between which spaces 32 of consider- 20 able size are formed to permit the exit of for- eign substances that might otherwise accumu- 25 late in the funnel, the two horizontally extend- ing ribs 30 forming a bearing or way against which the forward end of the plunger 18 bears. The funnel 29 is located on the knuckle side of 30 the car coupler. Couplers frequently slip by on this side in service, and when they do the ex- tent of slip-by is considerable and the funnels of opposing connector heads overlap, as shown in 35 dotted lines in Figure 2. Unless the coupling head C can pivot on the forward end of the yoke E the buffer spring F will be compressed solid as the couplers pass the full amount on this side, and will break or otherwise damage the bracket 40 B or the tie rod D. Pivoted as illustrated in this application the coupling head will, however, yield under coupler slip-bys on the knuckle side and move, if necessary, to the rather extreme positions shown by the dot and dash lines in 45 Figure 2. During such movement the plunger 18 is pushed rearwardly in its bearing in the lug 19, and against the tension of the buffer spring F, the housing 17 at this time sliding along the guide 16 on the rear end of the yoke. 50 At its extreme pivoted position the surface 33 of the head engages the adjacent side of the for- 55 ward end of the yoke to limit the pivotal move- ment of the head in this direction. Pivotal movement of the head in opposite direction is, 60 of course, prevented by the lug 27. This is done for the reason that coupler slip-bys on the guard arm side, which is the side this lug is located on, are of relatively short travel. The couplers almost never slip by on this side more than 5". 65 This amount of travel the compressional move- 70 ment of the buffer springs F in the opposing connectors can accommodate themselves to without damage. It is therefore not necessary to ar- 75 range the coupling head C so that it will swing to the right on its pivot pin 25 when the cou- 80 plers slip by on the guard arm side. Should such movement be at any time found desirable, however, the hereinafter described modification of my improvement provides it. 85 Any suitable means may be employed to at- 90 tach the usual train pipe hose 34 to the coupling head C. I preferably accomplish this by provid- 95 ing the hose with a suitable gasket carrying con- 100duit 35 which I pass through the coupling head 105 at an angle to the longitudinal direction of the connector, and removably lock the conduit in the chamber or housing 36 by a rugged plunger pin 37 extending through a wall of the chamber into 110 engagement with a semianular shoulder 38 on 115 the conduit. This construction is more fully il-

lustrated in Figures 2 and 4 of my Patent 1,970,- 80 980, August 21, 1934, which was co-pending here- 90 with. The forwardly extending base or horn 39 of the coupling head is provided with a blunt, and preferably hardened, nose 40 which is formed separately of the base 39 and is pressed thereinto. The nose may, of course, be made in- 95 tegral with the base 39 if preferred. When op- 100 posing coupling heads couple up in service the nose 40 settles into the rearwardly offset bear- 105 ings 41 formed on the front face of the lugs 41" and thus bring the conduits 35 of the mating 110 heads into accurate alignment. It will be noted that the bearings or heavy webs 30 and 31 which 115 cross the opening in the apex of the funnel are offset rearwardly a substantial distance from 120 the bearings 41. This is done to avoid the possi- 125 bility of foreign substances gathering on the in- 130 ner faces of these webs and interfering with the 135 proper seating of the nose 40 in the funnel.

The modification of my improved support shown in Figure 5 consists in substituting for the hereinbefore described plunger base 17 and plunger arm 18, a laterally extending lug 42 formed on the rear end of the yoke E. Between 140 this seat and the lug 19 I interpose a suitable 145 compression spring 43, preferably of the volute type. A cylindrical plunger 44 extends through the lug 19, the spring 43 and the seat 42, as 150 shown, the plunger being reduced in diameter 155 at 45 to form a shoulder for the forward end of 160 the spring 43. The spring serves to position the 165 coupling head C and resist pivotal movement 170 thereof the same as in the case of the previously 175 described construction of my invention. To per- 180 mit adjustment of the tension which the spring 185 43 exerts on the plunger 44 and the coupling 190 head C, I threadingly mount in the lug 42 an 195 adjustable seat 46 which receives and supports 200 the rear end of the spring 43. Spaced openings 205 47 are provided in the threaded shank 48 of the 210 seat to receive a suitable wrench or other tool 215 with which to adjust the seat.

In Figure 6 I show a modification of the plun- 220 ger 18 shown in Figures 1, 2 and 4. The con- 225 struction consists in providing twin plungers 18 and 18" located on diametrically opposite sides 230 of the housing or base 17. With this arrange- 235 ment the lug 27 on the forward end of the yoke E would be eliminated, thus allowing pivotal 240 movement of the coupling head to either the 245 right or left on its pivot pin 25.

It will, of course, be understood that the pres- 250 sure which the springs F and 43 exert on the 255 heads C must be sufficient to prevent undesired 260 movement of the head on its pivot 25, as in cou- 265 pling on sharp curves, etc. I have found that 270 500 pounds resistance gives satisfactory opera- 275 tion of the heads.

What I claim is:

1. An automatic train pipe coupling comprising in combination, a coupling head, a member pivotally connected thereto and extending rear- 280 wardly thereof, a bracket extending from above downwardly into said member, a tie rod project- 285 ing into the member and pivotally engaging said bracket, a spring anchored to the bracket by said tie rod and serving to press said mem- 290 ber forwardly, and a plunger engaging said head and said spring and cooperating with the latter to yieldingly resist pivotal movement of said head relative to said member.

2. An automatic train pipe coupling comprising in combination, a coupling head, a hollow member pivotally connected thereto and extend-

- ing rearwardly thereof, a bracket the lower portion of which extends into the hollow of said member, a tie rod projecting into the hollow of the member and mounted for pivotal movement relative to said bracket, a plunger comprising a base and a forwardly extending arm, and a spring anchored in place by said tie rod and engaging the base of said plunger and serving to hold said forwardly extending arm in engagement with said coupling head to yieldingly resist pivotal movement of the head on said member. 5
3. An automatic train pipe coupling comprising in combination, a coupling head, a hollow member extending rearwardly from the head and having on its rear portion a laterally extending projection, said head being pivotally connected to the forward end of said member, a bracket extending into the member with its rear face normally engaging said projection, a tie rod engaging the bracket and having pivotal movement thereon and extending rearwardly thereof, a spring surrounding said tie rod and serving to yieldingly urge said coupling head forward with the projection on said member yieldingly held 10 against the rear face of said bracket, and a plunger device interposed between said spring and said member and extending forwardly along the member into engagement with a rear side of said coupling head to resist pivotal movement of the head on said member. 15
4. An automatic train pipe coupling comprising in combination, a coupling head, a bracket, a member pivotally connected at its front end to said head and supported at its rear end on said bracket, a plunger movably mounted on said member and arranged to bear against said head at a point laterally of its pivotal connection to said member, and spring means for supporting said member on the bracket and for yieldingly maintaining said plunger against the head. 20
5. In an automatic train pipe connector, a coupling head, a member to which said head is pivotally connected, a bracket for supporting said member, a plunger arranged to yieldingly press against said head on one side of said pivotal connection, and a single spring for yieldingly maintaining said member on said bracket and said plunger in engagement with said head. 25
6. In an automatic train pipe connector, a coupling head of the pin and funnel type, a member to which said head is pivotally connected, a plunger bearing against said head on the funnel side of said pivotal connection, and a spring for yieldingly forcing said plunger toward said head. 30
